PENCIL LEAD

Isidor Chesler, West Orange, N. J., assignor to
 Eagle Pencil Company, New York, N. Y., a corporation of Delaware

Application July 6, 1934, Serial No. 733,979

4 Claims. (CL 120—83)

My present invention is concerned with pencil leads.

An object of the invention is to provide a pencil lead which, though of small diameter, without the need for pointing or sharpening the lead, is adapted to make a marking line surprisingly thin and sharp, compared to the diameter of the lead.

Another object is to provide a lead of the above type of universal applicability for various types of wooden and mechanical pencils now on the market, and which in the use of such pencils affords the specialized utility above alluded to.

Another object is to provide a lead of the above type, in which the above utility is attained, though the lead be solid in cross-section, as is a conventional lead, and is made of the conventional lead mix of filler, binder and graphite or pigment.

Another object is to provide a lead of the above type, by which the likelihood of breakage in the process of insertion of the lead into a mechanical pencil is minimized, without sacrifice in the security with which the lead is held in the mechanical pencil.

In the accompanying drawing, in which is shown one of various possible embodiments of the several features of the invention,

Fig. 1 is a side view of my preferred lead.

Fig. 2 is a view in longitudinal cross-section of the lead, on a greatly enlarged section, and

Fig. 3 is a view partly in cross-section showing the lead applied in one construction of mechanical pencil.

The invention in general comprises the use of a lead having a cross-section generally polygonal with an even number of sides alternately of greater and lesser length, the surface of the lead being depressed or concave between consecutive edges, which edges are equidistant from the axis of the lead.

In the accompanying drawing is shown a preferred embodiment of the invention in which the lead is generally octagonal in cross-section. The edges extend in pairs adjacent to each other, one pair being shown at 10° and each pair being separated from the neighboring pair by an interval greater than between the elements of the pair.

In a preferred embodiment, the edges are spaced by angular intervals, alternately of 30 degrees and 60 degrees, as shown. Each pair of edges thus extends in a plane parallel to the opposite pair of adjacent edges. As shown, the surface of the lead is depressed or rendered con-

cave as at 12 between consecutive pairs, and at 13 between each pair of edges.

In the preferred specific embodiment, all edges 10 are at a uniform distance from the axis 11 of the lead, in commercial practice for ordinary 5 mechanical pencils, preferably .023 inches. The concavity of each longer face of the lead may be as shown in the drawings on a radius of .049 inches and of .010 inches for the shorter faces. It is noted that the edges 10 while sharp 10 are determined by areas intersecting each other almost at right angles, and, accordingly, the edges have considerable mechanical strength compared to edges at sharply acute angles.

The lead is formed by extrusion in the conventional way, except that the die has the cross-section shown in Fig. 2, instead of the conventional circular cross-section.

In Fig. 3 is shown a cross-section of mechanical pencil equipped with the lead just described. 20 It is seen that the lead described is more easily engaged within the lead holding clutch 15 than is the ordinary round lead, for it engages such clutch only at some or all of the eight sharp points or apices 10 as it is inserted, and 25 any non-uniformity in either the lead or the clutch will not result in breaking of the lead, since the sharp apices will more readily wear off in the process of inserting the lead than would the entire periphery of an oversized or incorrectly centered circular lead. The same considerations apply from the standpoint of feeding the lead in use through the tapered point 16 of the mechanical pencil.

The details of the mechanical pencil illustratively shown in Fig. 3 need not be described for this is merely one of numerous possible conventional constructions in which the rear end of the lead is held by the clutch sleeve 15, which has a wing or offset 17 riding within a threaded 40 track 18 within the pencil casing 19 and is operated by means (not shown) preferably from the eraser end 20 of the pencil.

Only a point or apex 10 can touch the paper for writing; the depressed or concave surfaces 12 and 13, even though the pencil is but in the neighborhood of a 20th of an inch in diameter, cannot possibly reach the paper until the point or apex has been worn down. In ordinary use, the apices at the tip of the lead will all be worn down more or less uniformly and they must be worn down practically to their roots before the concavities 12 and 13, which now are no longer concavities can touch the paper, and by then, the point of the pencil will have been worn down to so small a diameter that 55

the writing line will be approximately as thin as could be made by one of the sharp apices. A new and complete, generally octagonal cross-sectional area of lead is now exposed for service, for repetition of the wearing action incurred in writing, as just set forth.

Inasmuch as all of the edges of my lead are equi-distant from the axis of the pencil, they lie on a cylindrical locus and, accordingly, the lead 10 is applicable to any and all mechanical pencils designed primarily for a circular lead and with all of the advantages above set forth in the use of the specialized form of lead described.

It will thus be seen that there is herein described 15 an article in which the several features of this invention are embodied, and which article in its action attains the various objects of the invention and is well suited to meet the requirements of practical use.

As many changes could be made in the above 20 article, and many apparently widely different embodiments of this invention could be made without departing from the scope thereof, it is intended that all matter contained in the above description or shown in the accompanying drawing 25 shall be interpreted as illustrative and not in a limiting sense.

Having thus described my invention, what I claim as new and desire to secure by Letters Patent 30 of the United States is:—

1. A pencil lead having sharp edges longitudinally thereof and equidistant from the axis of said lead, said edges distributed peripherally of the

lead in a plurality of pairs of contiguous edges, the pairs of adjacent edges being separated by a distance greater than the distance between the edges of any one of said pairs, the surface of the lead between each pair of said edges and the consecutive pair of said edges being concave.

2. A pencil lead generally polygonal in cross-section, having an even number of sides, and edges, each pair of edges in a plane parallel to another pair of edges, said edges distributed in 10 an even number of pairs of adjacent, parallel edges, each pair separated from the neighboring pair of edges by a distance greater than the distance between the edges of any one pair, the faces of said lead being concave between consecutive 15 edges.

3. A pencil lead having a cross-section polygonal in shape with an even number of edges, all equidistant from the axis of the lead, said edges distributed in an even number of pairs, the members of each pair spaced from each other by a constant angular interval, the angular interval between consecutive pairs being twice that between the members of each pair of edges, the lead 20 being concave between consecutive edges.

4. A pencil lead generally octagonal in cross-section with sharp edges equidistant from the axis of the lead, said edges spaced from each other by alternate angles of 30 degrees and 60 degrees, and the surface of the lead being concave between 30 consecutive edges.

ISIDOR CHESLER.
